UNITED STATES PATENT OFFICE.

RICHARD MARTIN, OF MINNEAPOLIS, MINNESOTA.

VAPOR-HEATING SYSTEM.

1,224,559.

Specification of Letters Patent.

Patented May 1, 1917.

Application filed May 1, 1916. Serial No. 94,625.

To all whom it may concern:

Be it known that I, RICHARD MARTIN, a citizen of the United States, residing at Minneapolis, in the county of Hennepin and 5 State of Minnesota, have invented certain new and useful Improvements in Vapor-Heating Systems; and I do hereby declare the following to be a full, clear, and exact description of the invention, such as will 10 enable others skilled in the art to which it appertains to make and use the same.

My invention relates to steam heating systems and more particularly to that type of low pressure steam heating systems generally designated as "vapor systems."

In heating systems of this character, it is desirable, under ordinary running conditions that means be provided for rapidly letting out all air which may accumulate 20 in the system. In vapor systems, it is also desirable that a partial vacuum be produced in the circulating connections between the radiators and boiler whenever the fire in the boiler burns low and the water in the boiler 25 drops below a predetermined low temperature. This partial vacuum assists in maintaining circulation of the very low pressure vapor (to-wit, vapor below atmospheric pressure) from the boiler to the radiators 30 when the fire is very low. Furthermore, the act of closing the air vent from the return pipe of the circulating system prevents air from flowing into the same when the fire is low.

35 Frequently, in vapor systems, or low pressure steam heating systems, either by accident or by design, a considerable steam pressure will be carried into the system; and at such time, it is, of course, necessary that 40 the circulating system be closed from the atmosphere, so as to prevent the escape of steam and water.

Hence, my invention provides, in one or 45 more of the return pipes of the heating system, an air vent, and provides an automatic valve mechanism which will close this air vent under two very different conditions, to-wit, whenever the pressure in the boiler is exceedingly low, or below a predetermined point, and also when the pressure 50 of the boiler is high, or above a predetermined point. Furthermore, this valve mechanism is adjustable, so that it will operate under variable or different prede-

termined relatively low and relatively high 55 pressures.

In the accompanying drawings which illustrate the invention, like characters indicate like parts throughout the several 60 views.

Referring to the drawings:

Figure 1 is an elevation showing a boiler, a single radiator and the circulating connections between the boiler and radiator, together with my improved valve mechanism or controller applied thereto;

Fig. 2 is a vertical section of the complete valve and valve controller;

Fig. 3 is a vertical section of the valve mechanism showing the same on a larger 70 scale than in Fig. 2; and

Fig. 4 is a detail in section on the line $x^4 x^4$ of Fig. 3.

The numeral 1 indicates the boiler and the numeral 2 the radiator or one of the 75 radiators of the heating system. The numeral 3 indicates a vapor supply pipe leading from the top of the boiler to the upper portion of the radiator 2, and the numeral 4 indicates a return pipe leading from the 80 lower portion of the radiator 2, back to the lower portion of the boiler. From the lower portion of the return pipe 4, the pipe 5 is extended upward and connected to the bottom of a float chamber 6, the intermediate 85 portion of which is horizontally aligned with the water line $y-y$ of the boiler. The upper end of this chamber 6 is connected to the lower end of a tubular valve casing 7 that is provided with a horizontal axially perforated partition 8, formed to afford a conical seat for a valve 9. This valve 9 has screw-threaded engagement with, and is adjustable on the threaded end of a vertical valve stem 10, which, at its 90 lower end, is equipped with a float 11 that rides on the surface of the water contained in the lower portion of the float chamber 6. The upper portion of the valve casing 7 also has a conical valve seat 12 that is 100 adapted to be engaged by a valve 13 which also has threaded engagement with the valve stem 10. The two valves 9 and 13 are preferably substantially alike, but are reversed. Furthermore, the valve 9 is provided with a small air passage 14, for a purpose which will presently appear. An air passage 15 is also formed in the upper 105

end neck of the valve casing 7, so that the upper portion of said casing is normally in communication wth the atmosphere, as shown, through a vent pipe 16 which may 5 lead to any suitable point of discharge.

The intermediate portion of the return pipe, 4, at a point above the water level of the boiler and of the float chamber 6, is connected to a vent pipe 17, which, in turn, 10 is connected to a port 18 formed in the valve seat 8. In Figs. 1 and 3, two such pipes 17 and two ports 18 are shown, but it will be understood that the said pipes 17 are extended from the return connections 15 to different radiators and that any desired number thereof may be employed, depending on the nature of the system in which the invention is incorporated.

Operation.

20 The operation of the device described is substantially as follows:

First assume that the valve 9 is set on the stem 10 and in respect to the float 11, so 25 that the said valve will be closed whenever the pressure in the boiler falls below one-eighth of an ounce per square inch, for example. Then, if the pressure in the boiler falls still lower than one-eighth of an 30 ounce, a partial vacuum will be produced in the return pipe and in the radiator. Then, when the fire is increased so as to again raise the pressure in the boiler, the said partial vacuum will be maintained 35 until the assumed pressure of one-eighth of an ounce is again produced in the said boiler and in the radiator, and this partial vacuum insures circulation of low pressure vapor at points below one-eighth of an 40 ounce and even at points below atmospheric pressure.

Then when the pressure in the boiler and radiator is increased somewhat above one-eighth of an ounce, such pressure will cause 45 the water in the float chamber 7 to rise, thereby raising the float 11 and causing the same to raise and unseat the valve 9, thereby opening the return pipe from the radiator to the atmosphere, through the port 18, the 50 upper portion of the valve casing 7 and the air vent 15. This will let out any air that may possibly, and usually will, from time to time, work its way into the heating system.

In different installations, the pressure in 55 the boiler at which the steam would commence to waste through the return pipe and the port controlled by valve 9, will vary, but for the purpose of illustration, we will assume such boiler pressure to be approximately one-half pound. In that event, the 60 valve 13 should be so adjusted on the stem 10 and in respect to the float 11, that it will close against the seat 12, and hence, close the vent 15, whenever the water in the float 65 chamber 6 is raised to an extent that it will

be raised when the boiler pressure is increased to one-half pound. This closing of the valve 13, as is evident, cuts off all connection between the return pipe and the atmosphere and renders the system a closed 70 circulating system which can operate under any desired high pressure.

The purpose of the air passage 14 in the valve 9 is to let atmospheric pressure into the upper portion of the float chamber 6 at 75 all times, except when the valve 13 closes the vent 15 and renders it a closed system. With this passage 14, the pressure in the boiler works against atmospheric pressure to raise the water in the float chamber 6, 80 when the valve 9 is closed, and when the valves 9 and 13 are both open, the pressure in the boiler and the pressure in the said float chamber 6 are nearly equalized, so that the water in said chamber 6 drops back to 85 substantially the level of the water in the boiler.

When the valve 13 closes the vent 15, due to relatively high steam pressure, the vent 18 will be opened, and the pressure in the float chamber 6 will then be nearly equalized with that of the boiler and radiator, but will be slightly lower, because of the loss in pressure of the steam or vapor, due to condensation in its passage through the 90 radiator and pipes. When, however, this near equalization takes place, the column of water in chamber 6 will slightly lower, thereby causing the valve 13 to open slightly, and permit the further discharge of air 100 through the vent 15. The valve 13 will therefore, under the conditions just noted, be repeatedly opened and closed at short intervals, and will be held closed for a considerable time only when the boiler pressure 105 is relatively high.

This improved system, under ordinary high pressure has all of the advantages of a constantly closed vacuum return system, and has the further advantage of much greater efficiency at low pressure and, as already 110 stated, will produce vapor circulation, even at pressure below atmospheric. The system also has the further advantage that it will work where the air line in the return connection is brought back on a line very close to the water line of the boiler, which is frequently necessary for low basements. By reference to Fig. 3, and noting the statements already made, it is evident that in the 115 construction illustrated, the complete air vent from the return pipe is through the pipe 17, port 18, the upper portion of the valve casing 7, and vent 15, and, as shown, also through the vent pipe 16. Obviously, this air vent and the valves controlling the same may be modified within the scope of 120 this invention.

What I claim is:

1. In a heating system, the combination 130

with a boiler, a radiator, a feed pipe between said boiler and radiator, and a return pipe between said radiator and boiler, of an air venting conduit tapping said return pipe 5 at a point above the water level of said boiler and leading to the atmosphere, a float chamber, partly above and partly below the water level of said boiler and connected to said boiler at a point below the 10 water level thereof, a float in said chamber, a valve actuated by said float and operating by a partial vacuum in the system, to close said air venting conduit, and an air conduit leading from said float chamber and arranged 15 to be opened when the first noted air vent is closed by low altitude of water in said float chamber.

2. In a heating system, the combination with a boiler, a radiator, a feed pipe between said boiler and radiator and a return pipe between said radiator and boiler, a float chamber partly above and partly below the water level of said boiler and connected to said boiler at a point below the 25 water level thereof, a valve casing having upper and lower valve seats, the latter being connected to said float chamber, an atmospheric air vent leading from the upper valve seat, a float in said float chamber having a 30 projecting stem, two valves on said stem, one for engagement with said lower valve seat, and the other for engagement with said upper valve seat, an air venting conduit leading from said lower valve seat and tapping said return pipe at a point above the 35 water level of the boiler, and a small air passage constantly connecting the upper portion of said valve casing to the upper portion of said float chamber.

3. In a heating system, the combination with a boiler, a radiator, a feed pipe between said boiler and radiator and a return pipe between said radiator and boiler, a float chamber partly above and partly 45 below the water level of said boiler and con-

nected to said boiler at a point below the water level thereof, a valve casing having upper and lower valve seats, the latter being connected to said float chamber, an atmospheric air vent leading from the upper 50 valve seat, a float in said float chamber having a projecting stem, two valves on said stem one for engagement with said lower valve seat, and the other for engagement with said upper valve seat, an air venting conduit leading 55 from said lower valve seat and tapping said return pipe at a point above the water level of the boiler, a small air passage constantly connecting the upper portion of said valve casing to the upper portion of said float 60 chamber, the said two valves being independently adjustable, one with respect to the other.

4. In a heating system, the combination with a boiler, a radiator, a feed pipe between said boiler and radiator, and a return pipe between said radiator and boiler, of a float chamber partly above and partly below the water level of said boiler and connected to said boiler below its water level, 65 a valve casing having interior valve seats at its upper and lower extremities, the said upper valve seat leading to the atmosphere and the said lower valve seat being connected to said float chamber and to said return 70 pipe at a point above the water level of the boiler, a float in said float chamber provided with a projecting stem, and two valves on said stem, one engageable with the said upper valve seat under upward movement 75 of the float and the other engageable with said lower valve seat under downward movement of said float.

In testimony whereof I affix my signature in presence of two witnesses.

RICHARD MARTIN.
